UNITED STATES PATENT OFFICE.

HARRY A. FREDERICK, OF CHICORA, PENNSYLVANIA.

WIRELESS TIE INSULATOR.

Application filed March 31, 1921. Serial No. 457,197.

To all whom it may concern:

Be it known that I, HARRY A. FREDERICK, a citizen of the United States, residing at Chicora, in the county of Butler and State of Pennsylvania, have invented certain new and useful Improvements in Wireless Tie Insulators, of which the following is a specification.

This invention relates to improvements in insulators for supporting current conveying cables or wires, in a firm and secure manner, without liability of accidental displacement, and doing away with the ordinary tie wire used for such purposes.

15 A primary object of the invention is the provision of an insulator of the above described character, simulating in appearance the ordinary insulator, and employing a non-frangible device for locking, and tying the cable or current wire to the insulator.

20 A further object of the invention is the provision of an insulator which is simple in construction, practical, and which utilizes the natural tension of a suspended wire 25 in locking the same securely to said insulator.

Other objects and advantages will be apparent during the course of the following detailed description.

30 In the accompanying drawing forming a part of this specification, and in which similar reference characters designate corresponding parts throughout the several views,

35 Figure 1 is a front elevation of the improved insulator.

Fig. 2 is a plan view of the improved insulator.

Fig. 3 is a cross sectional view of the improved insulator, showing details of construction thereof, and taken on the line 3—3 of Fig. 1.

In the drawings, wherein for the purpose of illustration is shown the preferred embodiment of my invention, the letter A designates the wireless tie insulator, which is mounted upon the ordinary wooden pin B', as in usual construction. The insulator A, comprises the body portion B; the brackets C formed integral with the body portion B, and the non-frangible insert D. The various parts of the insulator A, are adapted to support a cable, or conducting wire E.

The insulator A, is preferably formed of porcelain, glass, or some other insulating material, which due to the quality of insula-

tion required, is ordinarily of frangible material. The body portion B, simulates in appearance somewhat the ordinary tie insulator, and comprises the dome 10, and the base 11. The base 11, is provided with the ordinary grooves 12, formed by flanges 13, and is preferably provided with the dripping edge 14. A screw threaded aperture 15 is provided centrally and upwardly in the base 11, for the insertion of the screw threaded end 16 of the pin B'. The dome 10, is rounded, and preferably provided with a rectangular recess 17 extending transversely through the body portion, and for the free reception of the insert D. Substantially U-shaped brackets 20 and 21 are provided upon the body portion B, and extending outwardly from the arcuate side 23 of the body portion, in a diverging direction. The brackets 20 and 21, are in transverse alignment, and the openings 24 therein open from the top of the dome 10, and are likewise in alignment for the reception of a wire or cable E. The brackets 20 and 21, are of the same material as the body portion B, and preferably integral therewith. Seats 25 are provided, and which extend downwardly in converging relation to each other for a purpose to be subsequently set forth. Since the brackets 20 and 21 extend at an acute angle with respect to each other, that is, diverge slightly, it is preferred that the inner face 26 of the brackets 20 and 21 be arcuated to engage 90 the wire E without any liability of rupture of said wire due to frictional contact therewith.

The insert, or piece D as heretofore mentioned is of some non-frangible material, such as aluminium, although the material of which the same is formed need not necessarily be restricted to aluminium. The insert D, is of rectangular formation, and is provided for reception within the recess 17, the same being held therein by frictional engagement with the sides of said recess. In the preferred arrangement, the insert D extends entirely through the dome 10, however, the same may be disposed in a closed pocket in the dome. A hook 30 is provided integral upon the face 31 of the insert D, and said hook provides a groove 32, in alignment with the top of the seats 25 of the brackets 20 and 21, and in the preliminary placing of a wire cable E on the insulator A, said wire E is seated in the open-

- ings 24 of the brackets 20 and 21, and manually placed in the groove 32 formed by the hook 30. A second hook 34, is placed immediately below the hook 30, to provide a groove 35, extending below the seats 25 formed in the brackets 20 and 21. In fact, a plurality of hooks may be formed below the hook 30, and in appearance altogether similar to that of hook 34, for the same purpose for which the hook 34 is provided.
- In placing the cable E to be supported in locked engagement with the insulator A, said cable E is first positioned downwardly in the openings or recesses 24 formed in the brackets 20 and 21, until they assume a natural position upon the seats 25. As heretofore mentioned, the next operation will be that of manually inserting the wire cable E in the groove 32 formed by the hook 30.
- In this position, the horizontal continuity of the wire E is unbroken, as can readily be determined from the dot and dash lines shown in Figure 1 of the drawing. It is preferred however, in the majority of instances, that the wire E be clamped under its own tension to be securely locked to the insulator A. This operation is effective, by the use of a small prying tool, such as a crow bar, which is inserted intermediate the wire E, and the hook 34, and by means of leverage secured by said suitable tool, the wire E is crimped, until the same seats upon the arcuate surface of the seats 25, and said crimped portion of the wire E snaps into the groove 35 formed by the hook 34. In this position, there is little liability of accidental displacement of the wire E from the insulator A.
- From the foregoing, it can be seen that an insulator has been provided in which a non-frangible, and preferably metallic insert is used, the same being insulated from the wire E by means of the insulation upon the wire, and which is insulated in the dome 10, and cannot result in any loss of current

in said cables. This insert D, is of great importance in that the same insures a very durable insulator having its hooks 30 and 34 of non-frangible material. There is thus little liability of any of the parts of the insulator becoming broken, or out of order.

Various changes in the shape, size, and arrangement of parts may be made to the form of the invention herein shown and described, without departing from the spirit of the invention or the scope of the claims.

I claim:

1. An insulator, comprising in combination a body portion having a recess transversely therethrough, substantially U-shaped brackets formed integral upon said body portion, in transverse alignment, and a non-frangible insert mounted in said recess and arranged intermediate said brackets for locking a wire supported by said brackets. 60

2. In an insulator, the combination with a wire, of a body portion having a recess therein, substantially U-shaped brackets formed integral upon said body portion for supporting said wire, and an insert mounted 70 in said recess having a hook thereon, said wire adapted to be tensioned under said hook for locking it in supported position on said brackets.

3. An insulator, comprising in combination a body portion of frangible insulation, and having a transverse recess therein, substantially U-shaped brackets formed integral upon said body portion and in transverse alignment upon opposite sides of said recess, said brackets having their openings extending upwardly, and provided with downwardly converging wire receiving seats, and a non-frangible insert for said body portion recess, having a plurality of hooks thereon for adjustably locking a wire in supported position in the seats of said brackets. 80

HARRY A. FREDERICK.
